CLAIM

The ornamental design for a figurine of a baby giraffe, substantially as shown and described.

DESCRIPTION

FIG. 1 is a front end elevational view of the figurine of a baby giraffe showing our new design;
FIG. 2 is a rear perspective view of FIG. 1;
FIG. 3 is a side elevational view of FIG. 1;
FIG. 4 is a perspective view showing the side opposite that shown in FIG. 3; and
